KEY CASE.

Application filed April 5, 1926. Serial No. 99,694.

REISSUED

The invention relates to cases for keys. Cases of this particular type are made up from a strip of flexible material, such as leather or the like, the end portions of which are folded in overlapping relation over the central portion to form an enclosure. The end portions, or flaps, are secured together by suitable means, such as a glove fastener, which is usually applied centrally between the upper and lower ends of the case. Such ends are open but the key holders, being pivoted to the central portion of the case, are prevented from passing out of the case by the two overlapping flaps which bear down upon them. The key holders are usually mounted upon a nonflexible member which extends across the central portion of the case near its upper end and holds it in the desired flat form and the ends of this member lie approximately coincident with the lines of fold of said flaps and prevent the flaps from folding upon other lines which are closer together. At the lower end of the case there is nothing to hold the central portion of the case in flat form nor to prevent the flaps from folding along other lines which are closer together than the usual lines of fold. Consequently, if pressure is brought to bear on the sides of the case (defined by the lines of fold) and near the lower end thereof, the back or central portion of the case will bend rearwardly bringing the lines of fold of the flaps closer together at their lower ends and making them converge downwardly instead of remaining parallel. When this happens, the upper ends of the flaps are caused to separate and bulge out from the key holder supporting member, making a large opening through which some of the keys and their holders may drop out. That is, the flaps being pivotally connected intermediate their ends by the glove fastener, the inward movement of the flaps at their lower ends causes a separation of the flaps at their upper ends.

In order to overcome this difficulty, I provide my end portions or flaps with stiffening

or reenforcing members, which are attached to the outside ends and terminate approximately at the lines of fold. The reinforced flaps prevent the sides from being brought toward one another.

In my drawings:—

Fig. 1 is a perspective view of the case when open, showing the reenforced flaps. 55

Fig. 2 is a perspective view of the case in its folded position.

The case consists of a strip 10 of a flexible material, such as leather, and the end portions 11 and 12 are adapted to be folded 60 along the lines 13 and 14 over the central portion 15 and to be secured in overlapping relation by some suitable means, such as a glove fastener 16. To the end portions 11 and 12, I attach the reenforcing members 17 65 and 18 by sewing them on to the outside edges of the end portions. These reenforcing members terminate near the lines 13 and 14. From this arrangement it will be seen that the flaps are kept in their proper position and are prevented from assuming any other position. 70

To further utilize the flaps, the reenforcing members are left open at the ends along the lines 13 and 14 and may be used as 75 pockets for the reception of papers.

Having described my invention, what I claim is:—

A case for keys and the like, comprising, a strip of flexible material having a back 80 portion and a flap on each side thereof, said flaps being foldable in overlapping relation over said back portion, a series of holders for keys and the like supported from said back portion near the upper edge thereof, 85 and reenforcing members substantially co-extensive in width and length with the flaps and secured thereto along their outside edges, said members arranged to maintain the case in flat form and resist pressure applied to the sides of the case along the lines of fold of said flaps. 90
